AUTOMATIC ALARM CLOCK

Walter Kohlhagen, Waterbury, Conn., assignor
to The Waterbury Clock Company, Waterbury,
Conn., a corporation of Connecticut

Application March 16, 1936, Serial No. 69,074

7 Claims. (Cl. 58—19)

This invention relates to improvements in automatic alarm clocks.

One object of this invention is to provide an improved automatic alarm clock formed of simple elements readily manufactured and readily assembled to produce a durable efficient construction at low cost.

With the above and other objects in view, this invention includes all improvements over the prior art which are disclosed in this application.

In the accompanying drawings, in which one way of carrying out the invention is shown for illustrative purposes:

Fig. 1 is a front elevation of the movement of the alarm clock;

Fig. 2 is a bottom plan view of Fig. 1;

Fig. 3 is a rear elevation of a fragmental portion of the back-plate with the rear shut-off lever shown in section in relation thereto;

Fig. 4 is a sectional view on line 4—4 of Fig. 2;

Fig. 5 is a perspective view, partly broken away, of the construction shown in Fig. 4; and

Fig. 6 is a rear perspective view of a portion of the construction shown in Fig. 5.

In the description and claims, the various parts are identified by specific names for convenience, but they are intended to be as generic in their application as the prior art will permit.

Referring to the drawings, 10 and 11 are front and rear movement-plates connected together by pillars 12 and carrying the parts of the movement of an alarm clock.

The particular movement illustrated has an electric motor 13, preferably synchronous, which receives alternating current from wires 14 and 15. The electric motor is geared down within the casing 16 to provide a seconds center-arbor 17 which has a seconds pinion 18 secured thereto and in driving relation with a reduction-wheel 19 carrying a pinion 20 which in turn meshes with the minute-wheel 21 frictionally secured to the minute-sleeve 22. Mounted on the minute-sleeve 22 forward of the front movement-plate 10 is a minute-pinion 23 which meshes with the dial-wheel 24 having the dial-pinion 25 secured thereto and which in turn drives the hour-wheel 25^a rigidly secured to the hour-sleeve 25^b.

The dial-pinion 25 has secured thereto for current rotation therewith a secondary dial-pinion 26 meshing with an alarm-wheel 27 to which is secured the alarm-cam 28. The alarm-set arbor or staff 29 is frictionally mounted for rotation by means of the collar 30 secured to the arbor 29 and frictionally pressed against move-

ment-plate 11 by means of a compression-spring 31 pressing between the front movement-plate 10 and the collar 32 secured on the arbor 29.

The front end of the arbor 29 has secured thereto an alarm-set finger 33 in engagement with the alarm-cam 28. The alarm-wheel 27 and its alarm-cam 28 are mounted for limited longitudinal sliding movement on the arbor 29 while remaining in mesh with pinion 26, being normally held in outermost position by means of an alarm-control member 34 here shown in the form of a leaf-spring having its outer end provided with a latch-shoulder 35 adapted to be engaged by a latch 36 formed on an end-portion of a shut-off lever 37 pivoted at 38 on the front movement-plate 10.

A tension-spring 39 normally tends to swing the lever 37 in an anti-clockwise direction. The shut-off lever 37 may have an angle-extension lever 40 extending through the back-plate 41 and having movement back and forth in the slot 42 of the back-plate 41. If desired to provide a permanent shut-off for the shut-off lever, this may be accomplished by providing the notched portion 43, into which the outer end (shown in section in Fig. 3) of the extension lever 40 may be sprung. The shut-off lever 37 may be provided with an arm 44 provided with a fork 45 adapted to slidably engage a pin 46 carried by a lever 47 pivoted at 48 on the front of the front movement-plate 10. The other arm 49 of the lever 47 has a circular end 50 which slidably engages between the fingers 51 and 52 of a shut-off slide 53 slidably secured on the front of the front movement-plate 10 by means of the headed pins 54 and 55.

The upper end of the shut-off slide 53 has an angle-bend 56 adapted to be connected with a top shut-off plunger 57 which extends out through the top of the case of the alarm clock. Either the top shut-off plunger 57 or the shut-off extension lever 40 may be provided alone, or both may be provided on a clock, as desired.

The alarm-sounding member or bell 58 in the particular construction shown is electrically actuated by an electromagnet 59 receiving current through the wires 60 and 61. Bell 58 and electromagnet 59 are mounted on bracket 81 by means of screw 58^a, the bracket 81 being secured to movement-plate by rivets 81^a. The wire 61 is secured to a metal electric terminal 62 secured upon a plate 63 of insulating material which is secured to the movement-plate 10. Also secured on the insulating-plate 63 and spaced from the terminal 62 is a second terminal 64 which, with 55

the first terminal 62, form a pair of terminals. Each of the terminals 62, 64 has an electric contact 65 on the under-side of the insulating-plate 63, so as to form a pair of spaced-apart electric contacts 65 in position to be engaged by a metallic bridging-contact-member 66 pivoted or rockably mounted at 67 on a vertically-slidable plate or bar of insulating material 68 mounted to slide vertically through a lower opening 69 in a U-bracket 70 and through an upper opening 71 in the insulating-plate 63. The bridging-member 66 has a pair of lugs 66a at opposite sides of its lower end adapted to limit the rocking movement of the bridging-member by engagement of the lugs 66a with opposite edges of the bar 68.

The bar 68 extends through an opening 72 in the end of the alarm-control spring 34, which latter has its two sides 73 and 74 bent up and secured therein is a pin or rivet 75 which extends through a hole 76 in the bar 68. A wire 77 leads from the contact 64 to the electromagnet 59 for actuating the bell 58.

The pole-piece 78 of magnetic material of the electromagnet extends to a location adjacent the armature of magnetic material forming a hammer 79 secured to a leaf-spring 80, which latter is secured to the non-magnetic bracket 81. The bell or sounding-member 58 is also of magnetic material and forms the other pole-piece of the electromagnet 59, so that as the alternating current intermittently energizes the two pole-pieces 58 and 78, the armature or hammer 79 is caused to vibrate rapidly and strike the bell 58, thus producing the alarm.

In operation, the alarm-set arbor 29 is turned to bring the alarm-cam finger 33 to the desired position corresponding to the time it is desired that the alarm should sound. Alternating current being supplied to the alarm clock through the wires 14 and 15 results in the synchronous electric motor of the clock actuating the time-train and through the latter, as previously described, actuating the alarm-wheel 21, which latter makes one complete revolution in each twenty-four-hour period.

When the alarm-wheel 21 has been rotated to a position to bring the notch 82 beneath the cam-finger 33, the alarm-control member or spring 34 shifts the alarm-wheel 21 and its cam 28 vertically upwards, as seen in Fig. 2, and hence moves the outer end of the alarm-control spring 34 and the bar 68 upwardly, to thus carry the rockable bridging-member 66 into contact with the pair of electric contacts 65, whereupon current actuates the electromagnet 59 to cause the magnetic hammer 79 to strike the bell or sounding-member 58.

When it is desired to stop the alarm, this can be done by pressing down on the top shut-off plunger-rod 51 or by swinging the shut-off extension lever 40 downwardly, either of which procedures causes the latch 36 of the shut-off lever 37 to ride along the cam-surface 83 of the alarm-control spring 34 until the latch 36 snaps past the latch-shoulder 35, whereupon the alarm-control spring 34 springs upwardly to cause the latch 36 and latch-shoulder 35 to engage, thus holding the shut-off lever 37 in the position described. In this operation of latching the parts 35 and 36, the bar 68 has been forced downwardly and held in a position such as illustrated in Figs. 4 and 5, with the bridging-member 66 below and out of contact with the pair of contacts 65, thus break-

ing the electric circuit to the electromagnet 59 and stopping the sounding of the alarm.

As the time-train of the clock continues to operate, the alarm-wheel 21 continues to rotate to cause the sloping portion 84 of the alarm-cam 28 to engage the cam-finger 33 and thus depress the alarm-control spring 34, which presses the latch-shoulder 35 down away from the latch 36 to thus release the shut-off lever 37, which thereupon is pulled away from its latching position by means of the spring 39, thus automatically resetting the alarm, ready for actuation at the next twenty-four-hour alarm interval.

During the period of time from the unlatching of the shut-off lever 37 until the sounding of the alarm, the bridging-member 66 is held down out of contact with the electric contacts 65, as a result of the alarm-cam 28 and alarm-wheel 21 maintaining the alarm-control spring 34 depressed until the notch 82 of the cam 28 again registers with the alarm-cam finger 33, whereupon the alarm-control spring 34 again raises the bar 68 and the bridging-member 66 into engagement with the switch-contacts 65, to thus again sound the alarm.

If for any reason, it is desired to permanently shut off the alarm and not have it sound at its normal sounding times, this can be accomplished in any suitable way. One way is by springing the extension lever 40 laterally until it engages in the notch 43, thus permanently holding the shut-off lever 37 with its latch 36 in latching position above the alarm-control spring 34.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended to be embraced therein.

I claim:

1. An automatic alarm clock comprising: electric alarm-actuating mechanism including an electric switch having a closable portion; a spring-actuated alarm-control member connected to said closable portion and having a latch-shoulder; a spring-actuated alarm shut-off member spring-biased to inoperative position and having a latch to engage said latch-shoulder when the alarm-control member is in a position to allow actuation of the alarm thereby to hold said alarm-control member and alarm shut-off member against actuation by their respective springs; and release mechanism adapted to release said latch, and subsequently release said alarm-control member to move said closable portion of said electric switch to initiate the actuation of said alarm-actuating mechanism.

2. An automatic alarm clock comprising: electric alarm-actuating mechanism including an electric switch having a closable portion; a spring-actuated alarm-control member carrying said closable portion and having a latch-shoulder; a spring-actuated alarm shut-off member spring-biased to inoperative position and having a latch to engage said latch-shoulder when the alarm-control member is in a position to allow actuation of the alarm thereby to hold said alarm-control member and alarm shut-off member against actuation by their respective springs; and release mechanism adapted to release said latch, and subsequently release said alarm-control member to move said closable portion of said

electric switch to initiate the actuation of said alarm-actuating mechanism.

3. An automatic alarm clock comprising: electric alarm-actuating mechanism including an electric switch having a rockable, closable portion; a spring-actuated alarm-control member carrying said rockable, closable portion and having a latch-shoulder; a spring-actuated alarm shut-off member spring-biased to inoperative position and having a latch to engage said latch-shoulder when the alarm-control member is in a position to allow actuation of the alarm thereby to hold said alarm-control member and alarm shut-off member against actuation by their respective springs; and release mechanism adapted to release said latch, and subsequently release said alarm-control member to move said rockable, closable portion of said electric switch to initiate the actuation of said alarm-actuating mechanism.

4. An automatic alarm clock comprising: electric alarm-actuating mechanism including an electric switch having a closable portion; a spring-actuated alarm-control member having a slidable part carrying said closable portion and having a latch-shoulder; a spring-actuated alarm shut-off member spring-biased to inoperative position and having a latch to engage said latch-shoulder when the alarm-control member is in a position to allow actuation of the alarm thereby to hold said slidable alarm-control member and alarm shut-off member against actuation by their respective springs; and release mechanism adapted to release said latch, and subsequently release said slidable alarm-control member to move said closable portion of said electric switch to initiate the actuation of said alarm-actuating mechanism.

5. An automatic alarm clock comprising: electric alarm-actuating mechanism including an electric switch having a rockable, closable portion; a spring-actuated alarm-control member having a slidable part carrying said rockable, closable portion and having a latch-shoulder; a spring-actuated alarm shut-off member spring-biased to inoperative position and having a latch to engage said latch-shoulder when the alarm-control member is in a position to allow actuation of the alarm thereby to hold said slidable alarm-

control member and alarm shut-off member against actuation by their respective springs; and release mechanism adapted to release said latch, and subsequently release said slidable alarm-control member to move said rockable, closable portion of said electric switch to initiate the actuation of said alarm-actuating mechanism.

6. An automatic alarm clock comprising: electric alarm-actuating mechanism including an electric switch having a closable portion; a spring-actuated alarm-control member connected to said closable portion and having a latch-shoulder; a spring-actuated pivoted alarm shut-off member spring-biased to inoperative position and having a latch to engage said latch-shoulder when the alarm-control member is in a position to allow actuation of the alarm thereby to hold said alarm-control member and alarm shut-off member against actuation by their respective springs, and operating mechanism including a lever means connected to said alarm shut-off member; and release mechanism adapted to release said latch, and subsequently release said alarm-control member to move said closable portion of said electric switch to initiate the actuation of said alarm-actuating mechanism.

7. An automatic alarm clock comprising: electric alarm-actuating mechanism including an electric switch having a closable portion; a spring-actuated alarm-control member connected to said closable portion and having a latch-shoulder; a spring-actuated alarm shut-off member spring-biased to inoperative position and having a latch to engage said latch-shoulder when the alarm-control member is in a position to allow actuation of the alarm thereby to hold said alarm-control member and alarm shut-off member against actuation by their respective springs and having a spring hand-lever, and means adjacent the normal path of movement of said spring hand-lever into locking engagement with which said hand-lever may be sprung; and release mechanism adapted to release said latch, and subsequently release said alarm-control member to move said closable portion of said electric switch to initiate the actuation of said alarm-actuating mechanism.

WALTER KOHLHAGEN.
